UNITED STATES PATENT OFFICE.

MICHAEL HOGARTY, OF SALISBURY, CONNECTICUT.

RULE.

SPECIFICATION forming part of Letters Patent No. 465,664, dated December 22, 1891.

Application filed June 27, 1891. Serial No. 397,709. (No model.)

To all whom it may concern:

Be it known that I, MICHAEL HOGARTY, a citizen of the United States of America, residing at Salisbury, in the county of Litchfield 5 and State of Connecticut, have invented certain new and useful Improvements in Rules, of which the following is a specification, reference being had therein to the accompanying drawings.

10 This invention relates to certain new and useful improvements in rules, having reference more especially to the class of composite folding rules; and it has for its object the provision of means whereby there shall be a 15 great saving of material and the strength of the parts greatly improved.

To these ends the invention comprises a rule whose main or body portion is made of wood, and metallic side plates between which 20 and said wood body the hinge-plates are secured, the latter being covered or concealed by ivory strips secured to the wood body, substantially as hereinafter fully set forth, and particularly pointed out in the claims.

25 In the accompanying drawings, Figures 1 and 2 are opposite plan views of my improved rule. Fig. 3 is a longitudinal sectional view on the line $x-x$, Fig. 1. Fig. 4 is a cross-sectional view on the line $y-y$, Fig. 1. Fig. 5 is 30 a view of one of the sections.

As heretofore constructed, the objection to rules having ivory bodies has been, first, that the same was very expensive; second, that in many instances rivet-holes were made with 35 difficulty, and, third, that ivory if subjected to a sudden knock or fall would break at the point of location of the rivets. Another objection was to the time and labor involved in curving or tenoning the ends of the ivory sections. By my invention it is sought to attain 40 all the advantages of a solid ivory rule without entailing any of the objections thereto, and also to add additional strength to the parts and render a great saving in time and 45 cost of production.

Referring to the drawings, A designates what is commonly called a "foot-rule," composed of two main sections a , which are each divided into two sub-sections a' , a'' , said sections 50 being hinged or pivotally connected together. Each section is composed of a central body-piece b , of wood, and parallel longitudinal

side strips b' , of metal. The inner ends of the longitudinal strips b' of the end section a' have apertured ears b^2 formed therewith, and 55 through the apertures of said ears is passed a pin or rivet b^3 , which is also passed through apertured ears b^4 of two short hinge-plates b^5 , and also through a central sleeve b^6 , inserted between said ears b^4 , the whole constituting a 60 hinge C. The hinge-plates b^5 are greatly reduced in width and are designed to fit in grooves or recesses in the wood or body portion b of the second section a^2 and held sandwiched between the body and the longitudinal 65 side strips d by rivets d' , which pass through said strips and body. The ends of the wood body b are curved to fit the hinges.

D designates the strip of ivory for each section. The same is rigidly secured to the 70 wood body b by rivets D' and is held between and flush with the protruding edges of the side strips b' . The ends of the strips adjacent the hinge C are perfectly straight and made to fit flush against the hinge, concealing entirely 75 from view the hinge-plates. All curving or reducing of the ivory strips is thus avoided, and the strength of the latter at their ends is not impaired by having tenons and the like.

The hinge E between the sections a consists 80 of a central circular plate e , having a flange e' and two parallel hinge-plates e^2 , between the ears e^3 of which plate e is pivotally secured by a pin or rivet e^4 . The flange e' of plate e is rigidly secured between parallel 85 plates e^5 . The plates e^2 are secured by rivets to opposite sides of the wood body of one of the sections a^2 , while the plates e^5 are similarly secured to the other section. The outer ends of these plates e^3 , e^5 are preferably 90 provided each with a slight curve e^6 , and the ivory strips are correspondingly curved to conform thereto.

The rule is shown as having an extensible plate F, provided with a head f' ; but as this 95 feature forms no part of my invention further description thereof is unnecessary.

From the foregoing it will be seen that I have produced a rule that possesses all of the advantages of a solid ivory rule, yet is much 100 cheaper and far more lasting and durable, and one that presents a neat appearance, the hinge-plates of the intermediate sections being concealed by the ivory strips.

I claim as my invention—

1. A rule composed of a wood body, ivory strips covering said body and secured thereto, and longitudinal metallic plates inclosing the 5 side edges of said body and strips, as set forth.
2. A rule having its sections composed of a wood body, longitudinal metallic plates, the hinges between said sections having their plates sandwiched between said body and plates, and the strips or plates covering said body and hinge-plates and located between said longitudinal plates, as set forth.
3. The herein-described improved rule, consisting of the sections having each a body of

wood, longitudinal metallic plates secured to 15 the side edges of such body, the hinges having their plates sandwiched between said body and metallic plates, and the ivory strips secured to the opposite sides of said body and located between said longitudinal plates and having 20 flush ends covering said hinge-plates, substantially as set forth.

In testimony whereof I affix my signature in presence of two witnesses.

MICHAEL HOGARTY.
